(57) **CLAIM**

The ornamental design for a machine tool housing, as shown and described.

DESCRIPTION

FIG. 1 is a front, right side perspective view of a machine tool housing having the design;

FIG. 2 is a front elevation view thereof;

FIG. 3 is a right side elevation view thereof;

FIG. 4 is a left side elevation view thereof;

FIG. 5 is a rear elevation view thereof;

FIG. 6 is a top plan view thereof;

FIG. 7 is a bottom plan view thereof;

FIG. 8 is a front, right side perspective view thereof depicting sliding panels in an open position; and,

FIG. 8A is a front, right side perspective view thereof depicting sliding panels in an open position, the specific construction of the machine tool assembly revealed thereby forming no part of the invention as claimed.
